UNITED STATES PATENT OFFICE.

LEON W. BRODOWSKI, OF TRENTON, NEW JERSEY.

LOCK.

1,364,069.

Specification of Letters Patent.

Patented Jan. 4, 1921.

Application filed January 30, 1920. Serial No. 355,057.

To all whom it may concern:

Be it known that I, LEON W. BRODOWSKI, a citizen of the United States, residing at Trenton, in the county of Mercer and State of New Jersey, have invented certain new and useful Improvements in Locks; and I do hereby declare the following to be a full, clear, and exact description of the invention, such as will enable others skilled in the art to which it appertains to make and use the same.

This invention has relation to certain new and useful improvements in a lock and has for its primary object the provision of a lock which will be of such construction that the combination by which the lock will be operated must be known before the lock can be operated.

Another object of the invention resides in the provision of a lock of the above stated character which will not require a key but which will include several parts which must be turned and manipulated in a specific manner in order to actuate the locking bolt and the locking bolt operating plate.

The invention has for a further object, the provision of a lock of the above stated character which will be of simple construction and operation and which will be of such a character that the construction and arrangement of the operative parts may be readily varied to produce a new combination without materially altering the appearance of the operating parts on the outer side of the door to which the lock is applied.

The invention has for a still further object, the provision of a lock of the above stated character which will be of such a construction that some of the operating members must be placed in a certain position and held while other parts are operated to withdraw the locking bolt from its locking position.

With the above and other objects in view, as will appear as the description proceeds, the invention consists in the novel construction, combination and coöperation of parts as hereinafter more specifically set forth, claimed and shown in the accompanying drawings, forming a part of this application and in which:

Figure 1 is an elevation of a safe to which is applied the improved form of lock with the door in closed and locked position, the heads for operating the locking bolt engaging member and the plate raising member

being shown by dotted lines in their operated position.

Fig. 2 is an elevation of the rear side of the door carrying the improved form of lock with all of the parts in unoperated position.

Fig. 3 is a view similar to Fig. 2, showing the position of the parts after the locking bolt engaging pawl and the plate raising member have been moved to their operated positions to bring the locking bolt and withdrawing plate into alinement and interlocked engagement.

Fig. 4 is a view similar to Figs. 2 and 3, showing the locking bolt withdrawn from its locking position.

Fig. 5 is a detail transverse vertical section on the plane of line 5—5 of Fig. 3.

Fig. 6 is a detail view of the locking bolt removed.

Fig. 7 is a detail view of the withdrawing plate removed.

Referring more particularly to the drawings in which similar reference characters designate corresponding parts throughout the several views, 1 indicates the door of a safe 2 to which the improved lock has been applied. The lock includes a locking bolt 3 adapted to slide through the offset central portion or main portion of the bracket 4, having its opposite ends secured to the inner face of the door 1, adjacent the forward vertical edge thereof, as shown at 5. The bolt 3 is preferably flat and of elongated form with a rearwardly extended and downwardly directed tongue 6 formed on its rear or inner end and having a substantially V-shaped recess 7 formed in its upper portion to provide a notch and also a projection 8 with an inclined forward wall, as will be readily understood by referring to the drawings. The locking bolt 3 also has a notch 9 formed in its lower inner edge portion to provide a recess at the lower inner corner of the locking bolt 3 and also a projection 10 with inclined or beveled walls as will be readily understood and the purpose of which will presently be apparent.

The locking bolt withdrawing plate 11 is provided with an elongated longitudinal slot 12 in its main portion to accommodate the supporting pin 13 for the plate 11 and which pin is engaged through the slot 12 and secured in the door 1 to mount the plate 11 for sliding movement on the inner face of said door 1. The mounting pin 13 is provided with a suitable head 14 to retain the

plate 11 in proper position with respect to the door 1. The plate 11 is provided with a forwardly and upwardly directed tongue 15 for interlocking engagement with the tongue 6 of the locking bolt 3, as shown in the drawings. The withdrawing plate 11 is provided with a substantially V-shaped notch 16 in its upper forward end portion and a projection 17, one inclined wall of which is formed by the notch 16 and the purpose of which notch 16 and projection 17 will presently appear. A spring supporting post 18 projects from the inner side of the door 1, preferably above the supporting pin 13. The overlapped ends of the arcuate springs 19 and 20 are secured in the post 18, the free or opposite end of the spring 19 being secured upon the screw 21 mounted in the outstanding portion of the bracket 22 carried on the locking bolt 3 inwardly of the bracket 4. The corresponding end of the arcuate spring 20 is secured in a like manner upon the screw 23 mounted in the outturned portion of the bracket 24 carried on the withdrawing plate 11, outwardly or forwardly of the end of the slot 12 thereof, as shown in the drawings. It will be understood that springs 19 and 20 may be secured to the bolt 3 and plate 11 respectively in any other suitable and well known manner, if preferred. The spring 19 tends to force the locking bolt 3 outwardly to its locking position and the spring 20 serves to swing downwardly the forward end of the withdrawing plate 11 and thereby disengage the tongues 15 and 6 and break connections between the locking bolt 3 and the withdrawing plate 11. This will also place the withdrawing plate 11 in operative position, as will be clearly understood as the description proceeds. An elongated plate raising member 25 is mounted upon the inner end of a shaft 26 projecting through the door 1 and having an operating handle 27 upon its outer end. The free or operating end of the member 25 has an offset portion, thereby providing a shoulder for the lower edge of the plate 11 to rest upon when forced upwardly by the member 25, owing to rotation of the shaft 26 in either direction, the side edge of the member 25 forcing the plate 11 to swing upwardly upon the pin 13. The spring 20 also tends to hold resiliently the plate 11 in its outermost position, thereby causing the tongue 15 of the plate 11 to be in proper position for engagement with the outer wall of the tongue 6 of the locking bolt 3 so that these tongues may readily interlock, when the plate 11 is forced upwardly. The locking pawl 29 for the locking bolt 3 is mounted upon a shaft 30 projecting through the door 1 at a point below the inner end of the locking bolt 3, a head 31 being formed upon the outer end of the shaft 30 for the purpose of rotating the shaft 30 to bring the nose of the pawl 29 into engagement with the lower

edge of the locking bolt 3 for engagement with the outer wall of the projection 10 while the nose of the pawl catches in the notch 9 as the locking bolt 3 is drawn inwardly, as will be later fully described. It will be understood that the head 31 and also the head 27 on the shaft 26 are suitably spaced from the outer face of the door 1 so that they may be readily grasped and rotated and while the heads may be of suitable form as shown in its preferred form in Fig. 1 with the end of the elongated heads 31 and 27 curved in opposite directions so that they may be readily turned and held in proper position by the fingers to retain the pawl 29 and member 25 in proper position during operation of releasing and withdrawing the locking bolt 3. The withdrawing plate operating disk 32 has a peripheral extension 33 which is adapted to engage with the recess or notch 16 in the upper edge of the plate 11 and also engage the outer side of the projection 17 for forcing rearwardly the plate 11 when the member 32 is rotated in the proper direction. This member 32 is mounted on a shaft 34 having one end rotatably mounted in the main portion of the bearing bracket 35, which has its opposite ends offset and secured to the inner face of the door 1, above the plate 11, as shown at 36. The shaft 34 extends through the door 1 and has the head 37 formed upon its outer end and spaced from the outer face of the door 1, as clearly shown in the drawings. The head 37 preferably corresponds in form to the heads 27 and 31 and may be readily rotated by the thumb and one finger while other fingers are employed to hold the shafts 26 and 30 from rotating during operation of withdrawing the locking bolt 3.

When the locking bolt 3 is extended or in its locking position and the withdrawing plate 11 is disengaged therefrom, all of the parts should be in the position shown in Figs. 1 and 2 of the drawings.

When it is desired to withdraw the locking bolt 3 from its locking position, the handle or head 27 should be turned to cause the member 25 to move to its upstanding position and raise the plate 11 to horizontal position with the tongue 15 thereof interlocked with the tongue 6, as clearly shown in Fig. 3 of the drawings. The handle or head 31 should then be turned to move the nose of the pawl 29 to position between the forward lower corner of the plate 11 and the projection 10 of the locking bolt 3, as shown in Fig. 3 of the drawings. The heads 27 and 31 should then be held against farther movement in either direction by the fingers of the same hand to be employed in operating the lock or by the other hand of the operator. While the handles or heads 27 and 31 are held, the head or handle 37 should be turned in a counterclockwise di-

rection, thereby causing the projection 33 of the head 32 to engage in the notch 16 of the plate 11 and force the latter rearwardly together with the locking bolt 3, the nose of the pawl 29 automatically engaging back of the projection 10 and resting in the notch 9 in the lower edge of the locking bolt 3, thereby holding the locking bolt against forward movement. It will be evident that this movement of the plate 11 and locking bolt 3 is opposed by the springs 19 and 20. After the member 32 has been turned for some distance, the projection 33 thereof will ride out of the notch 16, but the pawl 29 will prevent the plate 11 and said locking bolt 3 from moving forwardly after the projection 10 engages the pawl 29. This will hold the lock in a partially withdrawn or unlocked position. The head or handle 37 should again be rotated in a counterclockwise direction to engage the projection 33 of the member 32 with the outer or forward edge of the projection 17 and as the member 32 continues to rotate, the plate 11 and locking bolt 3 will be forced farther inwardly until the locking bolt 3 is completely withdrawn or moved into operative position, as shown in Fig. 4 of the drawings. The door may be either opened or closed while the parts are held in this position. A further rotation of the head or handle 37, however, in a counterclockwise direction will release the projection 33 of the member 32 of the plate 11 and the springs 19 and 20, being under such a tension, will act to immediately return both the plate 11 and locking bolt 3 to their original positions. It will also be evident that movement of the member 32 in a reverse direction or disengagement of the member 25 from the plate 11 will permit the springs 19 and 20 to act to return all of the parts to their original position. It will therefore be seen that a knowledge of the construction and operation of the parts of the lock or at least a proper manipulation of the heads or handles 27, 31 and 37 must be necessary before the lock can be operated. It will also be evident that the number or arrangement of the notches and projections on the locking bolt 3 and plate 11 as well as the number and position of the members to be operated by the heads or handles on the outer side of the door 1 may be varied as desired, thereby changing the combination, without departing from the principle involved.

While the preferred embodiment of the invention has been shown and described, it will be understood that many minor changes in the details of construction and arrangement of parts may be resorted to within the scope of the appended claims without departing from the spirit of the invention.

What is claimed is:—

1. A lock comprising a locking bolt, a bracket for slidably mounting said locking

bolt on a door; a withdrawing plate for said locking bolt, means carried by said locking bolt and said withdrawing plate for interlocking engagement at times, said withdrawing plate being rotatively and slidably mounted on a door, a plate raising member for moving said withdrawing plate to locking engagement with said locking bolt and holding said withdrawing plate in such position, spring members for normally forcing said locking bolt and said withdrawing plate outwardly, means moving said withdrawing plate and said locking bolt inwardly against the action of said spring members, and means for automatic engagement with said locking bolt to hold the latter in its inwardly drawn position.

2. A lock comprising a sliding locking bolt, a sliding withdrawing plate for said locking bolt, means for forcing said withdrawing plate into alinement with said locking bolt, tongues carried by said withdrawing plate and said locking bolt for interlocking engagement, a spring member for resiliently forcing said locking bolt upwardly and outwardly, a second spring member for resiliently forcing said withdrawing plate outwardly and downwardly, means for causing an inward sliding movement of said withdrawing plate and said locking bolt when the latter is interlocked with said withdrawing plate, and a pawl for engagement with said locking bolt to hold the same against outward movement.

3. A lock comprising a sliding locking bolt, means for mounting said sliding locking bolt on one face of a door with its working end normally projecting past the edge of the door, a withdrawing plate having an elongated slot, means mounted on the side of the door and extended through said slot of the withdrawing plate to support the latter upon the door, a spring mounting post carried by said door, springs carried by said spring mounting post and connected with the locking bolt to normally force the latter outwardly, a second spring mounted on said spring mounting post and connected with the withdrawing plate to normally force the latter outwardly and downwardly from said locking bolt, tongues carried by the locking bolt and the withdrawing plate for interlocking engagement when said withdrawing plate is brought to alinement with the locking bolt, an operating member adapted for engagement with one end of said withdrawing plate to force the latter into alinement and interlocking engagement with the locking bolt, said operating member serving as means to force the latter and the locking bolt inwardly across said door, means for mounting the last mentioned means, and a pawl mounted on said door and adapted to be held in position to engage said locking bolt and hold the same against outward

movement when drawn inwardly by the withdrawing plate.

4. A lock comprising a bolt slidably mounted upon one side of a door and having 5 a tongue formed on its inner end, said locking bolt having a notch and projection in its lower edge, a slotted withdrawing plate, means for mounting said withdrawing plate upon the face of the door, said withdrawing 10 plate having a tongue formed on its forward end for interlocking engagement with the tongue of the locking bolt when said withdrawing plate is caused to swing to position in alignment with said locking bolt, said 15 withdrawing plate having a recess and a notch formed in its upper edge, means for swinging said withdrawing plate into alignment with said locking bolt, the last mentioned means projecting through the door 20 and being operable from the opposite side thereof, means operable on said opposite

side of the door for engagement with the notch and projection of the withdrawing plate when the latter is in alignment with the locking bolt to force said withdrawing plate 25 and locking bolt inwardly, means mounted on said door and connected with said withdrawing plate and said locking bolt to normally force the same outwardly and force the withdrawing plate downwardly, and 30 means operable from said opposite side of the door for engagement with the notch and projection on the lower edge of the locking bolt to hold the latter in its innermost position. 35

In testimony whereof I affix my signature in presence of two witnesses.
